STERILIZING DEVICE

John M. Hothersall, Brooklyn, N. Y., assignor to
American Can Company, New York, N. Y., a
corporation of New Jersey

Application November 9, 1939, Serial No. 303,695

3 Claims. (Cl. 219—47)

The present invention relates to a sterilizing device for fluid foods or the like and has particular reference to improved sectional heating tubes for sterilizing the fluid as it flows along a zig-zag or sinuous path of travel and which may be readily taken apart for cleaning.

An object of the invention is the provision of a fluid sterilizing device which is built up from a plurality of formed and disk members matched together to provide an annular zig-zag path of travel for the fluid and heated so that the fluid will be sterilized and agitated as it flows therethrough without danger of burning or scorching of the fluid particles.

Another object is the provision of such a sterilizing device which may be contained in a compact space and which may be readily taken apart for cleaning and which does not require the expensive spiral tubing ordinarily used for such purposes, and which at the same time is efficient in operation thus reducing sterilizing time.

Numerous other objects and advantages of the invention will be apparent as it is better understood from the following description, which, taken in connection with the accompanying drawing, discloses a preferred embodiment thereof.

Referring to the drawing:

Figure 1 is a longitudinal section of a sterilizing device embodying the instant invention, with parts broken away; and

Fig. 2 is a similar view of a modified form of the invention.

As embodiments of the invention, the single sheet of drawing illustrates a sterilizing device in which fluids such as milk, beer, creamed corn and the like are passed under pressure along an annular zig-zag or sinuous course of travel while subjected to a sterilizing heat. In the preferred form of device, as illustrated in Fig. 1, the heat for sterilizing the fluid is created by electric energy induced into metal parts of the device.

Such a sterilizing device includes a plurality of separate inner ring or disk members 11 which have outwardly extending annular fins 12 and a plurality of similarly separate outer ring members 13 which have inwardly projecting annular fins 14. The inner disk members 11 are mounted side by side in fixed position on a stationary bar or inner central support member 16.

One end of the bar 16 is formed with a head 17 which serves as a stop for locating the inner disk members 11 and for holding them in longi-

tudinal position in the device. The opposite end of the bar is threaded and is secured in a boss 19 formed integrally of a hollow liquid inlet housing 21. The boss is maintained in its central position within the housing by way of spider arms 22 which extend inwardly from the inside surface of the housing. The housing is connected to one end of a supply pipe 23 which leads to any suitable source of supply of the fluid to be sterilized.

The outer ring members 13 surround the inner disk members 11 and are retained in a side by side or contiguous position within a sleeve or outer tubular support member 25. One end of the sleeve is threaded into the housing 21, a gasket 26 being interposed between the end of the sleeve and a shoulder seat 27 in the housing in order to render the joint leak-proof. The opposite end of the sleeve which is adjacent to the head 17 of the bar 16 is formed with an inwardly extended shoulder 28 which serves as a stop for locating the outer ring members 13 in the sleeve.

This end of the sleeve 25 is also formed with a ground tapered seat 31 which fits against a similarly tapered seat 32 of a hollow fluid discharge housing 33 secured to one end of a discharge or outlet pipe 34. A coupling 35 rotatably carried on the housing fits over the end of the sleeve and is threadedly secured thereto for holding the tapered parts in tight leakproof engagement.

The annular fins 12 of the assembled inner ring or disk members 11 are equally spaced apart and thus set off U-shaped annular spaces 37 between them. The annular fins 14 of the assembled outer ring members 13 extend into these spaces, a fin 14 being in spaced relation to and between each pair of fins 12. A continuous zig-zag or sinuous annular channel 38 of uniform cross section is thus formed which extends throughout the entire line of assembled ring and disk members.

At the entrance end of this line of disk and ring members the channel 38 communicates with the interior of the fluid inlet housing 21 so that the fluid entering the device by way of the inlet housing will flow into and through the channel. In order to facilitate the entrance of the fluid into the channel, there are provided special inner and outer entrance disk and ring members 41, 42 which set off a straight annular entrance channel 43 between them and which leads into the sinuous channel 38. Adjacent these entrance disk and ring members there are also provided

inner and outer spacer washers 45, 46 and inner and outer resilient flanged gaskets 47, 48.

Thus the fluid entering the device by way of the inlet housing 21 not only passes into the sinuous channel 38 formed by the assembled ring and disk members but also presses against the flanged gaskets 47, 48. The force against the inner gasket 47 presses the inner disk members 11 tightly together in end to end relation and the force against the outer gasket 48 similarly presses the outer ring members 13 together endwise so that the fluid will be confined to the channel 38 and will be reduced to a thin film. As the fluid film flows through the channel, those fluid particles in engagement with the ring and disk member surfaces are displaced or rotated when they flow around the curves or corners in the channel and this displacement agitates the fluid sufficiently to prevent burning during sterilization.

At the exit end of the channel 38, provision is made for discharging the sterilized fluid film into the outlet housing 33. For this purpose there are provided special inner and outer end disk and ring members 51, 52 which are similar to the entrance rings 47, 48. These end ring sections set off between them a straight annular discharge channel section 53.

The heat for sterilizing the fluid film as it travels through the channel 38 is preferably imparted to the device by a high frequency electric induction coil 55. This coil may be one single long coil or may be a plurality of short coils connected in series. The coil or coils surround the sleeve 25 and are insulated therefrom by an insulating casing 56. Such a coil or coils may receive electric energy by way of lead wires 57, 58 and from any suitable source of electric energy. Electric energy passing through the coil sets up an electric field which extends through the inner and outer disk and ring members 11, 13 and the resistance to the passage of electric energy encountered in these members causes them to become heated. It is this heat which sterilizes the film of fluid passing through the channel 38.

With such a construction of sterilizing tube, less space is occupied and expensive coiled tubing heretofore used for such purposes, is done away with. Such a sterilizing tube is also readily adapted to adjustment as to the desired length of sterilizing time. This change of sterilizing time is effected by adding to or reducing the number of ring sections forming the tube. Thus lengthening the sinuous channel 38 or shortening the channel directly affects the sterilizing time of a given product. Another outstanding feature of such a sterilizing tube construction is its simplicity and the ease with which the ring and disk members may be removed and taken apart for cleaning.

Fig. 2 of the drawing illustrates a modified form of the invention in which steam is used as a fluid heating medium instead of electric energy as just described. In such a modified form, the inner disk members 11, 41, 51, spacer washer 45 and gasket 47 are all carried on a hollow tube or inner support member 61 which at one end is threaded into the boss 19 of the fluid food inlet housing 21. In this embodiment the boss 19 is formed with a passageway 63 which communicates with the interior of the tube 61. The boss passageway also extends through one of the boss spider arms 22 and communicates with the interior of a steam inlet

pipe 64 which is threaded into the fluid food inlet housing 21. This steam inlet pipe leads to any suitable source of steam.

At the opposite end, the steam tube 61 is formed with a disk member locating shoulder 66 which corresponds in its holding action to the bar head 17 of the preferred form. Adjacent the shoulder the end of the tube is formed with a ground tapered seat 67 which receives a similar tapered surface 68 of an outlet boss 69 formed as an integral part of the fluid food discharge or outlet housing 33. The outlet boss 69 is supported in its place inside the outlet housing by spider arms 71. The housing itself is threaded internally for threaded engagement on the outside of the outer ring section sleeve 25, as in the preferred form of the invention, but is here provided with a resilient gasket 72. Such a gasket is disposed in a seat 73 of the sleeve so that the housing may be turned down until the ground seats 67, 68 meet in a tight leak-proof joint.

The outlet boss 69 is formed with a steam outlet passageway 76 which, adjacent the ground joint, communicates with the interior of the tube 61. This passageway also extends through one of the spider arms 71 and communicates with a steam and condensate discharge pipe 77 which is threaded into the side of the outlet housing 33. This pipe completes a line of circulation for the steam through the interior of the sterilizing device so that the inner disk members 11 and their annular fins 12 may be maintained at the desired fluid food sterilizing temperature.

The outer ring members 13 and their annular fins 14 in this modified form of the invention are also maintained at a sterilizing temperature by steam which is circulated around the outside of the sleeve 25. The fluid food outlet housing 33 is formed with a long skirt or jacket section 81 which surrounds the sleeve 25 in spaced relation and which encloses a steam chamber 82. The terminal end of the skirt section fits within a sealing channel 84 of a conventional stuffing box 85 formed on the fluid food inlet housing 21. Thus the outlet housing 33 may be readily removed when it is desired to take the device apart for cleaning. The stuffing box is sealed with suitable gasket material 86 and a turn nut 87 completes the assembly to provide a leak-proof joint for the steam jacket.

Steam is circulated through the chamber 82 by way of an inlet pipe 88 and an outlet or drain pipe 89. These pipes are threaded into the jacket section 81 of the fluid food outlet housing 33. The inlet pipe leads to any suitable source of steam while the outlet pipe leads to a suitable place of discharge.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sterilizing device for fluids, comprising a plurality of separate contiguous inner disk members having annular fins setting off annular spaces therebetween, a plurality of separate contiguous outer ring members disposed around said inner disk members and having annular fins dis-

posed within the annular spaces defined by the annular fins of the inner disk members to set off a sinuous annular channel extending from one end of said assembled disk and ring members to the other, an inner central support member for holding said inner disk members and an outer tubular support member for holding said outer ring members, said support members being arranged for convenient dismantling of the disk and ring members for cleaning, each of said support members having adjacent an end thereof means for locating said disk and ring members in longitudinal relation with their respective annular fins spaced from one another, a resilient gasket disposed adjacent each support member and respectively engaging against an outer associated disk and ring member for receiving the pressure of the fluid to be sterilized entering into and flowing through the said sinuous channel, said pressure forcing said ring and disk members respectively into closer end to end engagement to prevent leakage of the fluid, and means for heating said assembled disk and ring members through said support members for sterilizing the fluid passing through said sinuous annular channel.

2. A sterilizing device for fluids, comprising a plurality of separate contiguous inner disk members having annular fins setting off annular spaces therebetween, a plurality of separate contiguous outer ring members disposed around said inner disk members and having annular fins disposed within the annular spaces defined by the annular fins of the inner disk members to set off a sinuous annular channel extending from one end of said assembled disk and ring members to the other, an inner central support member for holding said inner disk members and an outer tubular support member for holding said outer ring members, said support members being arranged for convenient dismantling of the disk and ring members for cleaning, each of said support members having adjacent an end thereof means for locating said disk and ring members in longitudinal relation with their respective annular fins spaced from one another, a resilient gasket disposed adjacent each support member

and respectively engaging against an outer associated disk and ring member for receiving the pressure of the fluid to be sterilized entering into and flowing through the said sinuous channel, 5 said pressure forcing said ring and disk members respectively into closed end to end engagement to prevent leakage of the fluid, and an electric heating coil surrounding said outer tubular support member for imparting heat to said assembled disk and ring members to provide sterilizing heat for the fluid passing through said sinuous annular channel.

3. A sterilizing device for fluids, comprising a plurality of separate contiguous inner disk members having annular fins setting off annular spaces therebetween, a plurality of separate contiguous outer ring members disposed around said inner disk members and having annular fins disposed within the annular spaces defined by the annular fins of the inner disk members to set off a sinuous annular channel extending from one end of said assembled disk and ring members to the other, an inner central tubular support member for holding said inner disk members and an outer tubular support member for holding said outer ring members, said support members being arranged for convenient dismantling of the disk and ring members for cleaning, each of said support members having adjacent an end thereof means for locating said disk and ring members in longitudinal relation with their respective annular fins spaced from one another, a resilient gasket disposed adjacent each support member and respectively engaging against an outer associated disk and ring member for receiving the pressure of the fluid to be sterilized entering into and flowing through the said sinuous channel, said pressure forcing said ring and disk members respectively into closer end to end engagement to prevent leakage of the fluid, and means for 10 circulating a fluid heating medium through said tubular support members to heat said assembled disk and ring members for sterilizing the fluid passing through said sinuous annular channel.
